HANDBAG

Jacob H. Klotz, Bronx, N. Y.

Application March 15, 1933, Serial No. 660,789

2 Claims. (Cl. 150—12)

This invention relates to hand-bags for holding and conveying purposes in general and provided with one or more suspending handles by which the bag is carried by the user.

The particular object of the invention is a hand-bag having a strong structure of both its load-holding portions and its handle or handles and particularly of the junctions of the load-holding portion and handle, and a handled handbag of attractive appearance and of extremely low cost as to bag, handle and bag-handle junctions.

The invention consists of the features and combinations described more fully below and shown in the drawings, of which:

Fig. 1 is an end elevation of one embodiment of the invention in a hand-bag in a common general form with two cooperating adjacent U-shaped handles.

Fig. 2 a detailed section showing the relative locations of certain portions of the bag of Fig. 1 and a portion of its handle at their junctions;

Fig. 3 a side elevation of the bag of Fig. 1, but the bag being opened in order to show how the parts are securely joined together in the relations of their junctions shown in Fig. 2;

Fig. 4 a view like Fig. 3, also with the bag open, but with both handles of Fig. 3 moved down, by means of the hinges involved in the invention, so as to show parts not possible to be shown in Fig. 3, as to the manner of sewing together the bag and its handles at their junctions;

Fig. 5 a view of the same bag closed, but with handle H₁ of Fig. 4 moved up on its hinges, and shown in section, in order to show more clearly the construction of the handle whereby it is put in useful form as to its portions both inside and outside the bag for the purpose of producing a structure wherein the bag and handle are most securely secured together and the hinged construction provided as a portion of a handle possessing high rigidity and ample strength; and

Fig. 6 is an elevation of another embodiment of the invention.

As indicated in Fig. 1, handles H, H₁ are longitudinally of ordinary general U-shape and symmetrically round or square, etc. in cross section, i. e., adapted to provide the best grip for the hands of the user carrying the bag. The bag itself is in general of usual but strong construction and attractive appearance.

When the bag is of the double-handle type, as shown, the construction of bag and handle, the relative positions of the parts, and the means for securing the parts together, all to be described, preferably are duplicated for each handle, as shown. Also the construction of the two ends of each handle preferably is the same, as shown.

As indicated in Fig. 2, including one end of

one handle, that end extends down into a position intermediate two long, flat, substantially straight flexible portions L and C of the bag structure, this being the reason why the extreme ends of the handles do not appear on the outside of the bag, Fig. 1. See such ends in dotted lines in Fig. 5, i. e., inside the bag-construction. Thus, each end of each handle is interposed between these long, flat, laterally flexible bag-portions L, C of Fig. 2, at the respective sides of the bag at its top bag-opening. In Figs. 1-4 the bag-part L is the so-called bag-collar and bag-part C is the bag-cover.

Fig. 2 shows that the extreme ends of the generally tubular handle lie substantially flat in clamping position between bag-parts L and C altho the rest of the handle includes a rigid metallic member T built in a generally tubular and flexible handle-cover K of thin leather, fabric, etc., as shown in Figs. 2 and 5. The flat, flexible bag-parts L and C are much longer than the widths of the two ends of each handle; the relatively narrow flat handle-ends lying flat between the bag-parts L and C which are very short relative to the much greater lengths of L and C.

Fig. 3 shows how the ends of handle H of Fig. 2, inside the bag, are secured to the laterally flexible bag-portions L, C, i. e., by means of the portions of the length of long stitch-line SL which secures long, flexible bag-collar L and bag-cover C to one another. These ends of handle H consist, as shown, only of the flexible material (thin leather or fabric, etc.) of handle-cover K; and bag-collar L and bag-cover C likewise are of any such or any other flexible material; so that in the embodiment shown, all three of these parts which are secured together by stitch-line SL are flexible and can and do bend laterally together desirably as a unit under all conditions of use. This provides for free mobility of handles H, H₁ toward and away from one another, as the result, in any case, of the flexibility and long lengths of L and C to which the ends of K are secured.

Preferably the handle-ends are secured to L and C by rivets V in addition to stitch-line SL. The above and the other features of the invention to be described constitute the structure of a high-grade bag which can be produced at extremely low cost of labor and materials. This construction will be understood better from Fig.

4, where handle H, in rear, has been pushed back on its hinges, down and out of sight so as to change the angular position of the bag-collar L and bag-cover C, of Fig. 2, and thereby show clearly the fact that the ends of the handle lie flat between bag-members L and C (of thin flexible fabric, leather, etc.), the rivets V extending thru L and C and the intermediate flat ends K₁ of flexible handle-cover K, just as the stitch-

line SL, shown in Fig. 3, likewise extends thru all three of said parts, L, K1 and C, the rivets V and the stitch-line SL cooperating in securing the flat handle-ends K1 in the position inside the bag between flat laterally flexible bag-parts L and C illustrated in Fig. 2. Altho the stitch-line SL alone provides a means for uniting those three parts securely together, yet it is preferred to employ the rivets in addition, because the bag and the handle are both of strong construction, the bag contents may be heavy, and it is desirable to provide for maximum strength of the means for securing the parts together in their relative position inside the bag as in Fig. 2. As shown in Fig. 5, altho the structure of the portion of handle H1 which extends outside the bag is of very rigid construction, yet the end portions of one of the elements of the handle H1 (as K as shown) which in the example shown are secured to the interior portions L, C of the bag, are very flexible, consisting as they do, of only the ends K1 of flexible handle cover K which is of flexible leather, real or imitation, or of fabric, the end portions K1 being comparatively thin, i. e., much thinner than the main handle portion H1 of symmetrical cross-section and extending in U-shape outside of the bag above the ends of metallic stiffening member T. These end portions K1 are not only of a thinness comparable with that of flexible bag-parts L and C, but like L and C are flat so that they conform with the flat flexible bag-parts L and C between which they are clamped and with which they are permanently united, and the combination of thin flat handle-ends K1 with laterally bendable bag-parts L and C is very strong, because the relative positions of the parts as shown in Fig. 2 are such that bag-parts L and C, on opposite faces of the flat handle-ends K1 strongly reinforce the latter so that when these parts are secured together, the entire areas of the flat handle-ends K1 are clamped securely between bag-parts L and C so that there is ample insurance against pulling out of the handle from the bag by any load likely to be carried in the bag. The lateral flexibility of bag-parts L and C provides for the desired lateral mobility of the handles relative to the bag as a whole, this being the case regardless of the flexibility of handle-ends K1 which project, flat, beyond the tubular handle-portion. Further important features of this construction are described infra. This strong but simple structure of extremely low cost is permitted because it is not complicated or made expensive by the amply rigid and strong metallic wire member T which is provided to stiffen and rigidly and strongly shape the U-shaped handle K as contrasted with its junction with the flexible bag-parts L and C in the relations shown in Fig. 2 to produce the hinge-effect which permits the usual movements of the handles relative to the bag as a whole. As shown in the various drawings, the portions of the flexible handle-cover K near the portions L and C of the bag are flared as they approach L and C and as they disappear inside the bag, i. e., they are flared at the portions of the handle-cover ends where the tubular handle H as a whole (cylindrical in section) begins to flatten as the ends of cover K at K1 are about to enter inside the bag and take the position shown in Fig. 2 and in dotted lines in Fig. 5 between flexible parts L and C. But at points not far above the bags and its part L, C, the handle H is shown as shaped as desired and strongly built by means of the rigid metallic wire mem-

ber T which extends throughout the horizontal portion of the handle and also down thru both its vertical portions, inside handle cover K. The securing of the projecting flat ends of one of the handle-elements to bag-portions L, C, when they are of flexible material as disclosed, thus not only provides strong joints between handle and bag, but the flat, laterally flexible bag-portions L and C act freely as hinges so that the handle can move freely to its various positions of Figs. 10-15, just as freely as in the previous more expensive types of hand-bags with costly metal fittings between bag and handle-ends, and notwithstanding the fact that here the normally flat joints or hinges consist of flexible portions of 15 the bag-parts L and C which flexibility is sufficient to provide for handle mobility regardless of any flexibility of handle-ends K1. Of course, the material of flattened tube-portions K1 of handle-cover K is sufficiently strong to withstand all 20 bending stresses at these points of hinging. And their strength at the hinge-portions is increased by additional structure to be described. Member T preferably is a rigid steel wire of about three-sixteenths inch diameter, more or less, so 25 that handle H is of built-in steel construction providing ample permanent rigidity and strength at parts of the handle where rigidity and strength are desired. But other metal than steel may be employed for this member T to impart substantially equivalent strength and rigidity, and in such cases said member may be of greater diameter, even as large as the inner diameter of flexible tubular handle-cover K, so as to give the desired good appearance to the handle and good 30 shape for the grip of the user's hand, in addition to strength and rigidity. But when, as preferred, member T is of steel and therefore can provide the desired rigidity by the relatively small diameter shown, (with correspondingly low cost for 35 the more expensive metallic parts) then the space between metallic stiffening member T and thin flexible cover K may be filled by any suitable means such as tube U of low cost felt, felt-paper or kraft-paper, etc. Usually tube U terminates with the ends of T, (because of its structural weakness not adapting it to project in flat form between flexible parts L and C) but it may extend down as far as to over-lap the handle-ends K1 shown in dotted lines in Fig. 5, provided 40 that U be of such nature as not to interfere with the construction and operation as above including the free hinge-action of flexible parts L and C joined to the flared, flat portions K1 of handle-cover K. Such tube U imparts transverse 45 stiffness to flexible and otherwise collapsible cover K. Member T and tube U may be and preferably are a single unit consisting of a regular article of manufacture including the above steel wire T as a core covered with paper U. Wire 50 T imparts longitudinal stiffness to the handle as above or other non-metallic material of low cost, such unit being enclosed by cover K. As indicated in Fig. 1, flexible tubular handle-cover K preferably consists of a flat strip of the desired 55 flexible material as above, of greater width than the circumference of tube U; K being laid around U and T, so that the edges of U overlap to a substantial extent and face one another at P where they are stitched together as shown in Fig. 1. 60 The bag of Figs. 1-5 is shown as provided with ordinary "zipper" closure Z. As usual, and as shown in Fig. 1, the stitched-together handle-cover-overlaps P of the handle-covers K face one another Fig. 1, so as to provide at the opposite 65 70 75

i. e., the outer, sides of the handles, smooth surfaces for the grip of the fingers of the user on the outer and lower sides of the two handles in positions adjacent one another in one hand of the user. But here this very facing arrangement of the portions P, P causes them, as shown in Fig. 3, to lie in positions where at first it might appear that they (extending in the direction of handle-movement toward adjacent positions of the two handles) would interfere with the free flexing of the flattened ends of handle-cover K at the portions where said ends are secured between flexible bag-portions L and C. But I have employed portions P, P usefully to increase (1) the strength of the flexible hinges between the handle-ends and the flexible bag-portions L and C, and (2) to increase the security of the fastening of the steel-built handle H to said flexible bag-portions, as follows. Before stitching the parts L, K and C together, as by S1, Fig. 3, in the relative positions shown in Fig. 2, the end portions P1, P1 of the stitched-together facing margins P, P of handle-cover K, at the flattened projecting ends K1, K1 of cover K, are bent sidewise over against the main portions of said flattened ends K1 of tubular cover K, Figs. 3 and 4. This increases the strength of the flattened hinge-portions K1 of handle-cover K by doubling their thickness altho it increases their stiffness, and furthermore it increases the security of the assembly of L, K1 and C, Fig. 2, by providing, flat between L and C, Fig. 4, four thicknesses of the not very strong material of K1, so that stitch-line SL secures together six thicknesses of flat material. The overlapping margins P, P of K, K are made wide enough to permit the above folding-over of P upon K.

In the modification of Fig. 6, the bag and handle constructions are similar to the above; and also as above, the stitch-line SL is the same as that which in Fig. 3 secures together the flat flexible bag-parts L, C and the flat flexible handle-ends K1. But in Fig. 6, where stitch-line SL secures the flat, quadrupled-material handle ends K1 to thin, flexible bag-part C, those ends K1 instead of extending into the bag-construction in locations in the interior of the bag as in Figs. 1-5, extend into the bag-construction at locations on the outside of the bag, i. e. flexible ends K1, stitched to bag-cover C as before, are stitched to the outside face of that cover C, as shown, instead of to its inside face and to flexible part L facing C. As in Figs. 1-5, rivets V may supplement SL here in Fig. 6, as shown in Figs. 3 and 4. In this case, since interior bag-part L (the bag-collar) is not used to clamp the handle ends K1 to bag-cover C, the outside strips L1, L2 (of fabric, leather, etc.) are employed in lieu of L, being stitched as shown at SL2 to the outside of bag-member C in positions such that the upper ends of L1 and L2, overlie, clamp and conceal the handle-cover ends K1, and also cover rivets V if used. Here in Fig. 6, however, the stitch-line SL as in Figs. 1-5, secures together parts K1 and C, said line SL not being applied until after L1 and L2 are stitched to C at SL2, so that line SL secures L1 and L2 to C in addition to securing the flat handle ends K1 to C; i. e., so that line SL secures together all three parts L1, K1 and C in Fig. 6 just as it (line SL) in Figs. 1-5 secures together the corresponding three

parts L, K1 and C. In Fig. 6 it is to be understood that L1, L2 may and usually do extend around the bottom of the bag to which they are secured. If desired the outside strips L1, L2 may be in the form of integral continuations of the flat handle ends K1. In any case, in Fig. 6, the bag-cover C (which is secured to thin flat ends of elements of the handles which project beyond the tubular portions of the handles) is of freely flexible material as specified above, so that the handles thereby can be moved freely as in more costly bags having expensive metallic fittings between bag and handle, irrespective of flexibility of handle-ends K1 themselves.

Having thus described certain embodiments of the invention, what is claimed is:

1. As an article of manufacture for combination with a hand-bag constructed with two flexible members having stitched-together facing-portions in the vicinity of its top opening, an exterior two-ended generally U-shaped handle including a flexible generally tubular non-metallic cover and a built-in metallic member therein imparting rigidity thereto, said handle-cover consisting of a long relatively narrow flexible strip substantially wider than the dimension of the periphery of said metallic member and laid around the latter with overlapping longitudinal margins of substantial width facing one another and secured together; said overlapping margins projecting laterally from the handle; and the ends of the handle-cover including said projections extending beyond the ends of said interior metallic member and said overlapping margins having sufficient width to enable them to be folded over on the main portion of said extending ends of the handle-cover, all whereby said ends and the overlapping margins folded thereover are substantially flat and flexible with four thicknesses of material and adapted for interposition between and securing to the two stitched-together flexible portions of the hand-bag.

2. The combination with a hand-bag constructed with two flexible members having stitched-together facing-portions in the vicinity of its top opening, of an exterior two-ended longitudinally U-shaped handle comprising interior and exterior correspondingly U-shaped elements which include a flexible generally tubular non-metallic cover and a built-in metallic member therein imparting rigidity thereto, said U-shaped handle-cover consisting of a long relatively narrow flexible strip substantially wider than the dimension of the periphery of said metallic member and laid around the latter with overlapping longitudinal margins of substantial width facing one another and secured together and projecting laterally from the length of the handle transversely of said mutually-facing stitched-together bag-members; the ends of said handle cover, including said secured-together overlapping longitudinal margins, extending longitudinally beyond the ends of said interior U-shaped metallic member, the extending tubular ends of the handle-cover being flattened and said laterally extending margins being folded over on them and such folded and extended structure lying substantially flat and in four thicknesses between said stitched-together bag-portions and secured thereto.

JACOB H. KLOTZ.
